[21] Appl. No.: 837,378

CLAIM

[22] Filed: Sep. 28, 1977

The ornamental design for a magnetic separator for particulate materials, as shown and described.

[51] Int. Cl. ..... D15—99

DESCRIPTION

[52] U.S. Cl. D15/147

FIG. 1 is a front elevational view of a magnetic separator for particulate materials showing our new design; FIG. 2 is an elevational view from one side; FIG. 3 is an elevational view from the other side; FIG. 4 is a back elevational view; and FIG. 5 is a top plan view.
